UNITED STATES PATENT OFFICE

114,175

DESIGN FOR A PLATE OR SIMILAR ARTICLE

William J. Frey, Grafton, W. Va.

Application January 28, 1939, Serial No. 82,649

Term of patent 3½ years

To all whom it may concern:

Be it known that I, William J. Frey, a citizen of the United States, residing at Grafton, in the county of Taylor and State of West Virginia, have invented a new, original, and ornamental Design for a Plate or Similar Article, of which the following is a specification, reference being had to the accompanying drawing, forming part thereof.

The single view is a plan view of a plate or sim-

ilar article, showing my new design, repeat units of which are shown between adjacent pairs of dotted lines, it being understood that the ornamentation shown is continued throughout the border of the plate.

I claim:

The ornamental design for a plate or similar article, as shown and described.

WILLIAM J. FREY.
